ATTORNEY.

UNITED STATES PATENT OFFICE.

JOHN W. ST. ORES, OF ELLENDALE, NORTH DAKOTA.

AUTOMOBILE HEADLIGHT.

Application filed November 8, 1927. Serial No. 231,853.

This invention relates to improvements in headlights for automobiles, and more particularly to a device to be combined with an ordinary headlight for reducing glare.

5 Recently there has been placed on the market, a material known as "celo-glass", which is formed of a sheet of ordinary wire netting impregnated or coated with a flexible transparent substance which renders the
10 netting imperforate.

I have discovered that if a disk or frusto-cone of this material is placed within the parabolic reflector of an ordinary headlight, and behind the light bulb, it will reduce the
15 glare.

The primary object of the invention is to combine with an ordinary headlight, a device made of celo-glass, which will reduce the glare from a headlight.

20 With the foregoing object outlined, and with other objects in view which will appear as the description proceeds, my invention consists in the novel features hereinafter described in detail, illustrated in the accompany drawing, and more particularly pointed out in the appended claim.

Referring to the drawing,

Fig. 1 is a side view of an ordinary headlight, partly in vertical longitudinal section, and showing my improvement applied thereto.

Fig. 2 is a transverse vertical sectional view, taken on line 2—2 of Fig. 1.

Fig. 3 is a plan view of the preferred form
35 of my attachment.

In the drawing, 1 designates the casing, 2 the parabolic reflector, 3 the light bulb and 4 the bulb socket of an ordinary headlight. I have used such a conventional form of headlight to disclose my invention, but I wish it understood that my attachment may be used with any lamp in which the light bulb is placed in front of a reflector.

My attachment is shown at 5, and it consists in the preferred form of a flat disk of celo-glass having an aperture 6 to receive the stem 7 of the light bulb, which stem is secured to the socket by the ordinary bayonet joint.

The disk, as shown in Fig. 1, may extend from the stem 7 to the inner surface of the reflector 2, but in practice, I prefer to make the disk of only slightly larger diameter than the light bulb, as I have found in practice that a disk of this size accomplishes the desired result.

The disk is formed of a base of wire netting 8, and the interstices of the netting are closed by a flexible transparent filling or coating 9, made of cellulose acetate or cellulose nitrate mixed with a suitable plasticizer; this mixture being dissolved with a suitable solvent. The filler or coating of such a disk expands and contracts with the metal of the netting, so that the disk is not affected by the heat from the light bulb.

From the foregoing, I believe that the invention may be readily understood by those skilled in the art, and I desire it to be understood that instead of employing a disk or the like of "celo-glass", I may employ a disk or the like of any material having the characteristics of "celo-glass".

What I claim and desire to secure by Letters Patent is:

An attachment for headlights, comprising a flat screen supported centrally between the light bulb and the reflector of the headlight, said screen consisting of an annular disk of wire netting impregnated with a flexible translucent, light diffusing and reflecting material.

J. W. ST. ORES.
